METHOD AND APPARATUS FOR THE PRODUCTION OF FASTENER ELEMENTS

Bruno Reiter, London, England, assignor to Ingenium Aktiengesellschaft, Chur, Switzerland

Application June 22, 1934, Serial No. 731,878
In Germany June 23, 1933

12 Claims.

(Cl. 153—1)

My invention relates to a method and apparatus for the production of fastener elements and more particularly to a method and apparatus for the production of said elements from a metal strip, which is advanced in its longitudinal direction.

The elements or teeth of sliding clasp fasteners must, as is known, be placed in position on the fabric strips or tapes with spread prongs or limbs which are then pressed together. It has up to now been usual to stamp the elements with spread prongs. An element with spread prongs is, however, wider between the extreme edges of the spread prongs than at its front part. It therefore seemed that a relatively considerable loss in material was absolutely unavoidable, if a plurality of elements was stamped. It has already been suggested to stamp the elements with closed prongs and to spread them subsequently before placing them on the fabric strips or tapes. The inventor has now found that if the prongs are spread subsequently it is possible to produce the elements without any waste. There arose, however, a particular difficulty which had likewise to be overcome. If one would pass a metal strip which would correspond to the width of the single element with closed prongs through the apparatus for the manufacture of the elements the advantage gained by the saving of material would be nullified, because such narrow strips are comparatively expensive.

One of the objects of my invention is to provide a method and apparatus, which permit an economical production of fastener elements from a metal strip being advanced in its longitudinal direction.

Another object of my invention is to provide a method and apparatus, which permit the punching of several adjacent rows of elements with closed prongs or limbs out of a single metal strip and spreading the limbs of the elements apart at the end of the strip, whereby an interference of the limbs of adjacent elements with each other is avoided.

In order to carry out my invention into practice, I advance a metal strip of a width equal substantially to the sum of the widths of several finished elements, the longitudinal edges of which being in contact with each other along their entire length, slit the leading end of the strip to form several branch strips each of which having substantially the width of a finished element, displace the branch strips to disengage their lateral edges from each other, preform the elements and their limbs in each of said branch strips, spread the limbs of the elements apart at the ends of the

branch strips, and sever the elements successively from the branch strips.

The invention further consists in an apparatus for carrying out the above-described method in which by a subsequent row of stamps the material is indented on both sides up to the middle in order to prepare it for the later operations. The apparatus is provided with a stamp for the production of indentations, the wedge of which is obtuse for the greater part, whereas the shorter part is more acute. The obtuse part effects indenting and pushing aside of the material for rendering the punching of this part with the subsequent punch possible, whilst the acute part preforms the ends of the limbs which later on grip the tape or fabric strip. A further row of stamps produces the recesses and projections forming the interengaging parts, which characterize the elements. A final row of stamps separates the finished elements from the divisions so that the indentation of the following part can be engaged by a stamp projection which is constructed as a mandrel at its front end and which spreads the preformed limbs apart. The apparatus therefore consists of several rows of stamps and a support for guiding the separate divisions set apart. The rows of stamps may naturally be combined with one another so that one row of stamps may also consist of fewer stamps. This is also true for the series of stamps so that the operation may be effected by a greater or smaller number of stamps.

The above mentioned objects and advantages as well as other objects and advantages will be more fully disclosed in the following specification reference being had to the accompanying drawing forming part of this specification in which:

Fig. 1 is a diagrammatical side view of the end of the apparatus, which forms the elements,

Fig. 2 is a horizontal sectional view taken on line 2—2 of Fig. 1 showing the metal strip in a top plan view,

Fig. 3 is a vertical sectional view taken on line 3—3 of Fig. 1 illustrating the guiding of the branch strips in different levels,

Fig. 4 is a top plan view of a finished element with closed limbs gripping a tape, the latter being shown in a sectional view,

Fig. 5 is a partial perspective view of a stamp and counter-stamp indenting the branch strip,

Fig. 6 is a partial perspective view of a stamp and counter-stamp indenting the branch strip.

Fig. 7 is a diagrammatical side view, similar to Fig. 1, of another embodiment of the apparatus, and

Fig. 8 is a horizontal sectional view taken on line 8—8 of Fig. 7.

Referring to Figs. 1 to 6, 1 designates a metal strip, which is fed into the apparatus by a suitable feeding device and is intermittently advanced in the apparatus in its longitudinal direction in the direction of the arrow 40. The metal strip 1 has a width A (Fig. 2) equal substantially to the sum of the widths a (Fig. 5) of three finished elements 41, the longitudinal edges 42 of which being in contact with each other along their entire length (see Fig. 2), or in other words, the width of the metal strip 1 is equal substantially to the sum of the widths of three juxtaposed finished elements 41 the limbs 43 of which being closed. The apparatus is provided with a guide 2 on which the metal strip 1 is advanced. At 29 the guide 2 branches into three channels 3, 3', 3''. The inner channel 3 is arranged at a level lower than the level of the outer channels 3' and 3'', as shown in Fig. 3, and is connected with the guide 2 by means of an inclination 30. A punch 4 arranged above the inclination 30 slits the strip 1 in three branch strips 5, 5', 5'' of a width a, a', a'' equal substantially to the width of a finished element and presses the inner branch strip 5 downwards to the inclination 30, if moved downwardly. A row of three stamps 8, 8', 8'' (Figs. 1, 2 and 6) and counterstamps cooperating with them (only the counterstamp 80 cooperating with the stamp 8 is shown in Figs. 1 and 6) is positioned above the channels 3, 3', 3'' at a point, where the inner channel 3 is again parallel to the outer channels although at a level set apart from the level of the latter, for a distance at least equal to the thickness of the metal strip. As best shown in Fig. 6 illustrating the stamp 8 and its counterstamp 80 as an example for all stamps and counter-stamps, each of the stamps 8, 8', 8'' and their counter-stamps are provided with V-shaped ends. The smaller parts 8a and 80a of said ends have an acute angle, while the greater parts 8b and 80b of said ends are provided with an obtuse or almost obtuse angle. If, for example, the stamp 8 reaches its lowest position, a small space s remains between the edges of the ends of the stamp 8 and the counter-stamp 80. Therefore, the stamps 8, 8', 8'' and their counter-stamps produce indentations in the upper and lower faces of the branch strips 5, 5', 5'', whereby the depths of the indentations are somewhat less than half of the thickness of the strip, so that a very thin membrane remains between the upper and lower indentations. The obtuse angled parts 8b and 80b of the stamp 8 and counter-stamp 80 displace the material of the branch strip 5 to some extent and facilitate a clean punching of the branch strip by the punch 9. The acute angled parts 8a, 8b, however, produce a small indentation 44 preforming the ends of the limbs 43 between the punch 9 and the stamp 10, as shown in Fig. 2. The obtuse angled parts of the stamps 8', 8'' and their counter-stamps cooperate likewise with each other to facilitate a clean punching of the branch strips 5' and 5'' by the punches 9' and 9'' and to produce the small indentations 44' and 44'' preforming the ends of the limbs between the punches 9' and 9'' and the stamps 10' and 10''. The stamps 10, 10', 10'' provided with depressions and their projecting counter-stamps 100, 100', 100'' produce projections 20, 20', 20'' and recesses 21, 21', 21'' respectively, which form the interlocking parts of the elements. Another row of punches 11, 11', 11'' is provided with projec-

tions 12, 12', 12'' which serve to remove the very thin membrane still existing between the ends of the limbs 43 and to spread the latter apart at the ends of the branch strips, if the punches or spreaders 11, 11', 11'' are moved downwards. It is possible to spread the limbs apart, although the metal strip has only the width of the sum of the widths of three adjacent finished elements, as the level of the inner branch strip 3 is set apart from the level of the outer branch strips 3', 3'' for a distance at least equal to the thickness of the metal strip, so that the lateral edges of the branch strips are disengaged from each other. The elements with opened limbs 43 are successively severed from the branch strips by means of suitable separating means. In a preferred embodiment of the apparatus, the punches 11, 11', 11'' sever the leading elements, which are advanced below said punches, and spread almost simultaneously the limbs 43 of the subsequent elements, now being at the ends of the branch strips, apart by means of the projections 12, 12', 12''.

The operation of the apparatus is as follows: The metal strip 1 is intermittently advanced step by step. During each standstill of the strip, the punches and stamps are moved downwards, whereby the punch 4 slits the strip 1 in branch strips 5, 5', 5'' and presses the inner branch strip 5 to the inclination 30, the stamps 8, 8', 8'' and their counter-stamps form the indentations, the punches 9, 9', 9'' produce the apertures 22, 22', 22'', the stamps 10, 10', 10'' and counter-stamps 100, 100', 100'' make the projections and recesses forming the interlocking parts of the elements, and the punches 11, 11', 11'' sever the leading elements from the branch strips and spread the limbs 43 of the subsequent elements apart. The finished element 41 with opened limbs 43 has the form as shown in Fig. 4, when it is delivered from the apparatus. The finished elements may be attached to a tape 45 by closing the limbs 43, which grip the tape and attach the element to the latter.

Figs. 7 and 8 show another embodiment of the apparatus, in which the branch strips 5, 5', 5'' are guided in the same level, but spread apart from each other so that spaces exist between the lateral edges of the branch strips sufficient to permit an opening of the limbs at the ends of the branch strips without any interference of the edges with each other.

Having now particularly described and ascertained the nature of my invention, and in what manner the same is to be performed, I declare that what I claim is:—

1. A method for the production of metal elements for sliding clasp fasteners, which consists in advancing a metal strip of a width equal substantially to the sum of the widths of several finished elements, the longitudinal edges of which are in contact with each other along their entire length, slitting the leading end of the strip to form several branch strips each of which has substantially the width of a finished element, displacing the branch strips to disengage their lateral edges from each other, preforming the elements and their limbs in each of said branch strips, spreading the limbs of the elements apart at the ends of the branch strips, and severing the elements successively from the branch strips.

2. A method for the production of metal elements for sliding clasp fasteners, which consists in advancing a metal strip of a width equal substantially to the sum of the widths of several fin-

ished elements, the longitudinal edges of which are in contact with each other along their entire length, slitting the leading end of the strip to form several branch strips each of which has substantially the width of a finished element, placing the branch strips in different levels set apart from each other for a distance at least equal to the thickness of the strip, preforming the elements and their limbs in each of said branch strips, spreading the limbs of the elements apart at the ends of the branch strips and severing the elements successively from the branch strips.

3. A method for the production of metal elements for sliding clasp fasteners, which consists in advancing a metal strip of a width equal substantially to the sum of the widths of several finished elements, the longitudinal edges of which are in contact with each other along their entire length, slitting the leading end of the strip to form several branch strips each of which has substantially the width of a finished element, spreading the branch strips apart from each other to provide a distance between their lateral edges, preforming the elements and their limbs in each of said branch strips, spreading the limbs of the elements apart at the ends of the branch strips, and severing the elements successively from the branch strips.

30 4. A method for the production of metal elements for sliding clasp fasteners, which consists in advancing a metal strip of a width equal substantially to the sum of the widths of several finished elements, the longitudinal edges of which are in contact with each other along their entire length, slitting the leading end of the strip to form several branch strips each of which has substantially the width of a finished element, relatively displacing the branch strips to disengage their lateral edges from each other, providing indentations in the branch strips at spaced intervals, punching the indented material to form the limbs of the elements, producing recesses and projections on the branch strips to form the interlocking parts of the elements, spreading the limbs of the elements apart at the ends of the branch strips, and severing the elements successively from the branch strips.

5. A method for the production of metal elements for sliding clasp fasteners, which consists in advancing a metal strip of a width equal substantially to the sum of the widths of several finished elements, the longitudinal edges of which are in contact with each other along their entire length, slitting the leading end of the strip to form several branch strips each of which has substantially the width of a finished element, relatively displacing the branch strips to disengage their lateral edges from each other, providing indentations in the upper and lower faces of the branch strips at spaced intervals, punching the indented material to form the limbs of the elements, producing recesses and projections on the branch strips to form the interlocking parts of the elements, spreading the limbs of the elements apart at the ends of the branch strips, and severing the elements successively from the branch strips.

6. A method for the production of metal elements for sliding clasp fasteners, which consists in advancing a metal strip of a width equal substantially to the sum of the widths of several finished elements, the longitudinal edges of which are in contact with each other along their entire length, slitting the leading end of the strip to

form several branch strips each of which has substantially the width of a finished element, relatively displacing the branch strips to disengage their lateral edges from each other, providing indentations in the branch strips at spaced intervals, partially punching the indented material to form apertures between the limbs of the elements, producing recesses and projections on the branch strips to form the interlocking parts of the elements, removing the remainder of the material between the ends of the limbs and spreading the latter apart at the ends of the branch strips, and severing the elements successively from the branch strips.

7. In an apparatus for the production of metal elements for sliding clasp fasteners, the combination of means for intermittently advancing a metal strip, means for slitting the leading end of the strip into several branch strips, means for relatively displacing the branch strips and disengaging their lateral edges from each other, means adapted to preform the elements and their limbs in each of said branch strips, spreaders adapted to open the limbs of the elements at the ends of the branch strips, and means adapted to sever the elements successively from the branch strips.

8. In an apparatus for the production of metal elements for sliding clasp fasteners, the combination of means for intermittently advancing a metal strip, means for slitting the leading end of the strip into several branch strips, means for relatively displacing the branch strips in different levels, guiding means adapted to lead the branch strips in said different levels, means adapted to preform the elements and their limbs in each of said branch strips, spreaders adapted to open the limbs of the elements at the ends of the branch strips, and means adapted to sever the elements successively from the branch strips.

9. In an apparatus for the production of metal elements for sliding clasp fasteners, the combination of means for intermittently advancing a metal strip, means for slitting the leading end of the strip into several branch strips, means for spreading the branch strips apart from each other, guiding means adapted to lead said branch strips spread apart from each other, means adapted to preform the elements and their limbs in each of said branch strips, spreaders adapted to open the limbs of the elements at the ends of the branch strips, and means adapted to sever the elements successively from the branch strips.

10. In an apparatus for the production of metal elements for sliding clasp fasteners, the combination of means for intermittently advancing a metal strip, means for slitting the leading end of the strip into several branch strips, means for displacing the branch strips and disengaging their lateral edges from each other, stamps for providing indentations in the branch strips, punches for removing the indented material and forming the limbs of the elements, stamps and counter-stamps for producing recesses and projections on the branch strips to form the interlocking parts of the elements, spreaders adapted to open the limbs of the elements at the ends of the branch strips, and means adapted to sever the elements successively from the branch strips.

11. In an apparatus for the production of metal elements for sliding clasp fasteners, the combination of means for intermittently advancing a metal strip, means for slitting the leading end of the strip into several branch strips, means for displacing the branch strips and disengaging their lateral edges from each other, stamps provided

- with V-shaped ends for producing indentations in the branch strips, said ends having a smaller part with an acute angle and a greater part with an angle of greater degree than the angle of the smaller part, punches for removing the material indented by the greater parts of said ends to form apertures between the limbs of the elements, stamps and counter-stamps for producing recesses and projections on the branch strips to form the interlocking parts of the elements, spreaders adapted to remove the remainder of the material between the limbs and to open the latter at the ends of the branch strips, and means adapted to sever the elements successively from the branch strips.
12. In an apparatus for the production of metal elements for sliding clasp fasteners, the combination of means for intermittently advancing a metal strip, means for slitting the leading end of the strip into several branch strips, means for displacing the branch strips and disengaging their lateral edges from each other, stamps provided

with V-shaped ends for producing indentations in the branch strips, said ends having a smaller part with an acute angle and a greater part with an angle of greater degree than the angle of the smaller part, counter-stamps provided with V-shaped ends having angles corresponding to said angles of the stamps, said stamps and counter stamps producing the indentations in the upper and lower faces of the branch strips at spaced intervals approximately to the middle of the 10 branch strips, punches for removing the material indented by the greater parts of said ends to form apertures between the limbs of the elements, stamps and counter-stamps for producing recesses and projections on the branch strips to 15 form the interlocking parts of the elements, spreaders adapted to remove the remainder of the material between the limbs and to open the latter at the ends of the branch strips, and means adapted to sever the elements successively from 20 the branch strips.

BRUNO REITER.
